UNITED STATES PATENT OFFICE.

CHARLES F. BUDROE, OF DAYTON, CHIO, ASSIGNOR TO THE DAVIS SEWING MACHINE COMPANY, OF DAYTON, OHIO, A CORPORATION OF OHIO.

COMBINED GASOLENE AND OIL TANK.

1,177,378.

Specification of Letters Patent. Patented Mar. 28, 1916.

Application filed November 17, 1914. Serial No. 872,642.

To all whom it may concern:

Be it known that I, CHARLES F. BUDROE, a citizen of the United States, residing at Dayton, in the county of Montgomery and State of Ohio, have invented certain new and useful Improvements in Combined Gasolene and Oil Tanks, of which the following is a specification, reference being had therein to the accompanying drawing.

This invention relates to a combined gasolene and oil tank and is designed more particularly for use in connection with motor-cycles, although it may be useful in connection with other fluids and for other purposes.

The available space on a motorcycle for the support of the various machinery, containers, etc., is very limited and the arrangement must necessarily be very compact. It has been customary to mount the gasolene container upon the horizontal frame member, thereby supporting the tank in a convenient position and in a position which is so far above the engine as to enable gravity to be utilized in feeding the gasolene, or other explosive fluid, to the engine. It is also desirable that the oil receptacle should be so arranged that a gravity or drip feed can be utilized. To accomplish this it is, in practice, necessary that the oil receptacle should also be mounted upon or close to the horizontal frame member. As it is not practical or desirable to mount two separate receptacles or tanks on the frame member it has been the practice heretofore to combine these two receptacles in one. To this end it has been customary to provide the gasolene tank with a false bottom spaced far enough from the real bottom of the tank to form an oil receptacle of the desired capacity. While this arrangement has the desired characteristic of compactness it was open to serious objections in other respects. One of the principal objections was the tendency of the partition to spring a leak, thus allowing the gasolene to mix with the oil. The gasolene tanks usually contain about two and one-half gallons of fluid and are frequently over two feet in length. It will be apparent, therefore, that when the machine is being ridden over a rough road or even over a comparatively smooth road, the gasolene will be caused to move from one end of the tank to the other and will acquire considerable momentum, thus imposing a severe

shock upon the tank and particularly upon the partition which forms the bottom wall of the gasolene receptacle. This action of the fluid within the receptacle, combined with the vibration to which the tank is subjected independently of the movement of the fluid, results in frequent leaks. Further, the construction of such a tank is such that it is necessary to remove one of the soldered walls of the tank to gain access to the partition and it is then not infrequently necessary to remove the partition itself. This operation involves a large amount of work and makes the repairing of a leak very expensive.

The object of the present invention is to provide a combined gasolene and oil tank having all the desirable qualities of the tank now in use and avoiding the undesirable features thereof.

To this end it is a further object of the invention to provide a tank having a body portion to contain the gasolene and having formed therein a chamber in which is mounted a separate receptacle for the oil.

A further object is to so arrange the wall or walls which form the chamber as to reinforce and stiffen the walls of the tank; and it is also an object of the invention to so arrange the walls of the chamber within the gasolene receptacle that they will extend into the path of movement of the fluid therein, thus tending to retard this movement and reduce the shock caused by the movement of the fluid.

In the accompanying drawings, Figure 1 is a horizontal sectional view taken on the line *x x* of Fig. 2 and looking in the direction of the arrows; and Fig. 2 is a longitudinal sectional view taken on the line *y y* of Fig. 1.

In these drawings I have illustrated one embodiment of my invention and have shown the same as applied to a tank designed to fit in the upper part of the frame of a motorcycle. It will be obvious, however, that the particular shape of the tank is not an essential part of the invention as this shape is well known and in common use. As here shown the tank comprises a main or body portion 1 shaped at its ends to fit in the angle of the frame of the motorcycle and having an outlet 2 leading to the carbureter. Mounted within this body portion 1 is a partition or wall 3 which forms

a chamber within the body portion of the tank. The character and arrangement of the partition or wall may vary to adapt the same to particular circumstances, but, in the present instance, I have shown the same as comprising an angular wall 3 rigidly secured at its upper and lower edges to the top and bottom walls of the body portion of the tank and having its end portions secured to one of the lateral walls of said body portion, thereby forming a chamber rectangular in cross section, as shown in Fig. 1. This wall being rigidly connected to the top and bottom walls of the body portion of the tank serves to brace and reinforce those walls against vibration, due either to the travel of the motorcycle or to the movement of the fluid within the tank. Further, the wall forming the compartment extends into the path of the fluid as it moves lengthwise of the elongated body portion of the tank, thereby retarding this lengthwise movement and materially reducing the impact and shock due to the same. Preferably, the chamber formed by the walls 3 is not used as a receptacle for the fluid but serves to receive a receptacle 4 which is formed separately from the body portion and is shaped to fit snugly within the chamber, within which it may be removably secured in any suitable manner. In the present instance, the top of the oil receptacle 4 is provided with flanges 5 and the top wall of the body portion is provided with a recess extending about the chamber to receive these flanges so that when the receptacle is secured in position within the body portion the top wall of the receptacle is substantially flush with the top wall of the body portion of the tank, thus giving the tank a smooth, finished appearance. The oil receptacle 4 may be removably secured in the chamber by any suitable device but, in the present instance, I have provided screws 6 for this purpose, which screws extend through the flanges 5 and into sockets formed in the wall of the body portion 1. The top wall of the receptacle 4 is provided with a screened filling opening 7 and the usual pump 8. These devices are well known and do not form a part of the present invention. In the present arrangement, where the chamber extends from the top to the bottom of the body portion of the tank, the bottom wall of the chamber is provided with openings, as shown at 9 and 10, to receive the discharge nipples 11 and 12, by means of which the oil is fed from the receptacle 4 to the points of consumption. This arrangement materially facilitates the assembling of the two parts of the tank as it is only necessary to remove one or two parts carried by the nipples to enable the receptacle 4 to be bodily removed from its chamber.

It will be apparent, therefore, that I have provided a combined gasoline tank and oil receptacle which is not only of a strongly reinforced construction and is of such a character as to reduce the shock due to the movement of the fluid therein, thereby reducing the liability of leakage, but that the oil is supported in a receptacle independently of the walls forming the chamber in the body portion of the tank. Consequently, even should these walls spring a leak, which is not likely to happen in the present construction, the gasoline could not reach the oil in the receptacle 4; further, the receptacle 4 being removably mounted in the chamber access can very readily be had to the walls of the chamber to repair any leak which may occur therein.

While I have shown and described one embodiment of the invention it will be understood that this has been chosen for the purposes of illustration only and that I do not desire to be limited to the details of construction shown and described, for obvious modifications will occur to a person skilled in the art.

Having thus fully described my invention, what I claim as new and desire to secure by Letters Patent, is:—

1. In a tank of the character described, a fluid tight body portion having an opening in its top adjacent one side thereof, a fluid tight partition arranged in said body portion to form a chamber, said partition having its ends attached to said side and spaced from the ends of the body portion, one edge attached to the bottom and its other edge attached to the top of said body portion and encircling said opening, and a receptacle mounted within said chamber and having one wall arranged to close the opening.

2. A tank of the character described comprising a fluid tight body portion, a fluid tight partition arranged in said body portion to form a chamber having one end open, and a receptacle filling said chamber and having one wall arranged to close the open end of said chamber, the outer surface of said wall being substantially flush with the surface of said body portion.

3. A tank of the character described comprising a fluid tight body portion, a fluid tight partition arranged in said body portion to form a chamber having one end open, and a receptacle filling said chamber and arranged to close the open end thereof, said receptacle having a discharge nipple extending through the wall of the body portion at the other end thereof.

4. A tank of the character described comprising a body portion, a fluid-tight partition arranged in said body portion to form a chamber and having one end open, and a receptacle mounted in said chamber and having one wall arranged to close the open end.

of said chamber, the outer surface of said wall being substantially flush with the surface of said body portion, said wall having portions overlapping the adjacent portions 5 of said body portion to receive fastening devices.

5. In a device of the character described, a body portion constituting an outer chamber adapted to hold a fluid, a partition forming 10 with a portion of said body portion an inner chamber adapted to hold a fluid of a nature different than the first-mentioned fluid, said inner and outer chambers being fluid tight with respect to each other, said 15 inner chamber being spaced from the ends and a side of said outer chamber, thereby acting as a baffle.

6. In a device of the character described, a body portion constituting an outer chamber adapted to hold a fluid, a partition in 20 said chamber bracing the top and bottom of said body portion, said partition forming with a portion of said body portion an inner chamber adapted to hold a fluid of a nature 25 different from the first-mentioned fluid, said inner and outer chambers being fluid tight with respect to each other and said inner chamber with its partition constituting a

baffle to retard the movement of the fluid in said outer chamber.

7. In a device of the character described, a body portion constituting an outer chamber, a partition in said chamber forming 30 with a portion of said body portion an inner chamber, said inner chamber having an opening 35 extending through said body portion, said inner chamber being spaced from the ends and a side of said outer chamber, and a receptacle mounted in said inner chamber and having one wall arranged to close 40 the opening therein.

8. In a tank of the character described, a fluid tight body portion, a fluid tight chamber mounted within said body portion and spaced from the ends and a side thereof 45 whereby said chamber acts as a baffle, a receptacle mounted within said chamber, said receptacle having a discharge nipple extending through the wall of the body portion.

In testimony whereof, I affix my signature in presence of two witnesses.

CHARLES F. BUDROE.
